UNITED STATES PATENT OFFICE.

WILLIAM B. REANEY, OF BALTIMORE, MARYLAND.

TRACTION-RAILROAD.

SPECIFICATION forming part of Letters Patent No. 281,924, dated July 24, 1883.

Application filed April 3, 1882. (No model.)

To all whom it may concern:

Be it known that I, WILLIAM B. REANEY, a citizen of the United States, and a resident of Baltimore, Maryland, have invented certain 5 Improvements in Traction-Railroads, of which the following is a specification.

My invention relates to that class of railways in which an underground traction-rope is used for traversing the cars; and the objects 10 of my invention, which is fully described hereinafter, are to make a substantial road of this class, to afford ready access to the underground tubes and pulleys for the traction-rope, and especially for affording facilities for altering 15 ordinary street-railways to traction-roads.

In the accompanying drawings, Figure 1 is a perspective view illustrating my improvements in traction-railroads; Fig. 2, a transverse section on the line 1 2; Fig. 3, a transverse section on the line 3 4, and Fig. 4 a view drawn to a reduced scale and illustrating the mode of applying my improvement to existing tracks.

A A are the opposite sills or longitudinal sleepers, and a a the usual rails, of an ordinary street-railway.

The structure to which my invention relates consists of a succession of sections, B B' B'', &c., of cast-iron, each section being composed 30 of a central tube, b, and certain arms referred to hereinafter, the tube being by preference about eight feet long and about twelve inches in internal diameter, and having in the top and from end to end a contracted longitudinal 35 opening, d, bounded by two flanges, e e, which also extend from end to end of the tube. The slot is for receiving the device by which the car is connected to the traction-rope; but as this device forms no part of my present invention, further allusion to it here will be unnecessary. From each side of the tube of each 40 section project arms f, f', and f'', three arms on each side being deemed sufficient for a tube eight feet in length; but it should be understood that I do not restrict myself to the length of the tube in each section, nor to any specific number of arms. The end arms f and f'' may be lighter than the intermediate arm or arms, for the end arms f'' of one section are bolted 45 to the end arms f of the adjoining section, the united arms being therefore as strong as the solid intermediate arms. While these arms

may be secured to flanges on the tube, I prefer to cast the arms on the tube, as shown. Each arm is provided with two lugs, i i, one 55 fitting to one side and the other to the opposite side of the longitudinal sill or sleeper beneath which the arm extends. At suitable intervals I make on one of the sections, preferably on every fifth section, an enlargement, h, 60 (best observed in Fig. 3,) this enlargement extending laterally beyond the tube and downward below the same, so as to form a chamber, G, communicating with the tubes of all the sections. 65

A pit, H, lined preferably with wood, is made in a street at a short distance from the railway-track, this pit, which is covered by a movable plate, m, communicating with the chamber G through a passage, I. 70

To the bottom of the chamber G is secured a standard, n, in which is a bearing for one of the journals of the grooved pulley K, on which the traction-rope M bears, the bearing for the other journal of the pulley being in a bracket, 75 p, secured to the closed side of the chamber G.

Any water which may gain access to the pit H or to the tubes or chamber G is drained off from the latter through a pipe, w, which communicates with any neighboring sewer. 80

The bottom and sides of the passage I, between the vault H and chamber G, may be of wood; but the top consists, by preference, of a cast-iron plate, q, for supporting the pavement, one end of the plate resting on a ledge, 85 y, of the extension h, and the other end fitting against the lining of the vault.

On removing the cover-plate m of the vault, access can be had to the chamber G and to the pulley and its bearings, and the pulley can be 90 readily removed and a new pulley introduced without disturbing the roadway.

While my invention may be advantageously adopted in making new traction-roads for street-cars, it is of especial advantage in altering ordinary horse-car roads to traction-roads, without materially interfering with the passage of cars while the alterations are being made. In laying one of the sections, for instance, a trench just large enough to admit the central tube of a section is dug midway between the two rails of the track, and transverse trenches just large enough to admit the arms, such transverse ties as may be in the way be- 95 100

ing removed, after which the section is introduced into its place in the manner shown in Fig. 4, the arms of one section being passed beneath one of the sills far enough to permit 5 the depression of the other arms, after which the section may be elevated, its arms and lugs properly adjusted to the undersides of the sills, and the trenches filled and properly packed. All this may be done during the night, when 10 the travel of cars on the track has ceased, or when the ears succeed each other at long intervals.

The vault, being outside the track, can be made, as also the passage I, without interfering 15 with the travel of the cars.

I do not claim a traction-rope tube made in sections and having cast on it projecting arms for supporting the track-sills; but

I claim as my invention and desire to secure 20 by Letters Patent—

1. The within-described section of a traction-rope tube, having at each end arms constructed for attachment to the arms of adjoining sections, substantially as set forth.

2. The combination of a section of the traction-rope tube and an enlargement, *h*, forming a chamber, *G*, with a vault, *H*, made outside the track, and with a passage forming a communication between the vault and chamber, substantially as specified. 25

In testimony whereof I have signed my name to this specification in the presence of two subscribing witnesses. 30

W. B. REANEY.
